UNITED STATES PATENT OFFICE.

GEORGE WILLIAM GRAY, OF HOUSTON, TEXAS.

METHOD FOR CONVERTING HIGHER-BOILING PETROLEUM HYDROCARBONS INTO LOWER-BOILING PETROLEUM HYDROCARBONS.

1 193,541.

Specification of Letters Patent. Patented Aug. 8, 1916.

Application filed January 23, 1913. Serial No. 743,714.

To all whom it may concern:

Be it known that I, GEORGE WILLIAM GRAY, a citizen of the United States, residing at Houston, in the county of Harris and State of Texas, have invented certain new and useful Improvements in Methods for Converting Higher-Boiling Petroleum Hydrocarbons into Lower-Boiling Petroleum Hydrocarbons, of which the following 10 is a specification.

My invention consists of novel processes of converting higher-boiling petroleum hydrocarbons of complex molecules into lower-boiling petroleum hydrocarbons of simpler 15 molecules.

In an application for a patent filed by me on even date herewith bearing Serial No. 743,713, I have described novel processes for converting higher-boiling hydrocarbons into 20 lower-boiling hydrocarbons.

My present invention is a modification of said processes, by means of which I am able to use higher and less carefully regulated temperatures than there described, while obtaining 25 separately naphtha or gasolene; and, while using said higher temperatures, may convert substantially all the higher-boiling hydrocarbons into naphtha or gasolene; or, if preferred, may convert the same into 30 naphtha and illuminating oil obtained separately.

Naphtha is a general term which includes a number of different grades of gasolene. Naphtha, illuminating oils, etc., are made up 35 of individuals having different boiling points. In making a distillation test on a sample of naphtha or gasolene, for example, a quantity is introduced into a flask provided with a thermometer; the outlet of the 40 flask being connected to a condenser. Heat is gradually applied. The temperature at which the first liquid drops into the receiving flask is called the "initial boiling point." From time to time when the flow 45 of liquid ceases, the temperature is slightly raised. The temperature at which no oil is left in the flask is called the "end boiling point." Gasolene or naphtha is a product which will begin to distil anywhere from

50 about 70° to 150° F., and will all distil off below a temperature of about 350° to 400° F.; while illuminating oil is a product which will begin to distil anywhere from

about 310° to 320° F., and will all distil off below a temperature of about 600° F. 55

The term "end boiling point" in the specifications and claims is used to designate the highest boiling point of any of the constituents of commercial naphtha or illuminating oil. Since in nature there is no line 60 of division between these substances, and since the commercial line of division has changed and is subject to change in the future, no more definite term can be used and no more definite figures can be given. For 65 example, it is a matter of common knowledge that as the demand for naphtha or gasolene has increased much more rapidly than the demand for illuminating oil and as improvements have adapted gas engines 70 to utilize heavier grades of gasolene, the end boiling point of commercial gasolene has progressively risen, and the initial boiling point of commercial illuminating oil has correspondingly risen. 75

Whatever may be the end-boiling-point of commercial naphtha or of illuminating oil, the principle remains the same—that is to say, if the temperature of the vapor given off is maintained not above 325° F., substantially 80 the whole body of the higher-boiling-point hydrocarbons may be, if desired, converted into hydrocarbons having boiling points not above that temperature; and if the temperature is maintained not 85 above 350° F., substantially the whole body may be, if desired, converted into hydrocarbons having boiling-points not above that temperature. The same principle exactly would apply if, in the future, commercial 90 naphtha should include constituents having boiling-points as high as 400° F., or higher.

In the accompanying drawings I have shown one form of still which is suitable for use in the practice of my process, although 95 it will be understood that any other form of still which is suitable may be used.

In the drawings A is the still.

B is a shaft rotated by a pulley C and gears D. The shaft B carries stirring blades 100 E, E', the lower blades E' carrying depending chains F.

G are splash plates attached to the shell of the still.

H is a manhole, and I a discharge opening 105 at the bottom.

J is the vapor exhaust pipe and K is an inlet pipe for oil and chemicals. The pipe J leads to a chamber N from which a vapor pipe O leads to the condenser. This chamber 5 N represents diagrammatically one or more cooling chambers of any suitable construction (various different constructions being now well known).

As an example, I may take 100 parts of 10 petroleum distillate freed from naphtha products—such as gas oil made from a paraffin or semi-paraffin or semi-asphalt crude oil—and add to it 5 parts of a suitable agent—such as anhydrous aluminum chlorid 15 for example. The mixture is then heated to a temperature above the end-boiling-point of naphtha. As explained in my said application, so long as the hydrocarbons in the still are not heated to produce a vapor substantially above the end-boiling-point of 20 naphtha—say about 400 degrees F.—the vapors driven off will contain little or no illuminating oil, or hydrocarbons of higher boiling-point than naphtha; but, when the 25 temperature is increased substantially above that point, illuminating oil will be driven off, and this will be condensed in the cooling chamber, or chambers, diagrammatically indicated by N in the drawings, so that only 30 naphtha or gasolene will pass to the condensing chamber. If it is desired to convert all the oil into naphtha, the illuminating oil collected in the chamber N is returned to the still by the pipe M, where it is again acted 35 on by the reducing agent and the heat. If preferred, however, it may be drawn off from the cooling chamber, as is well understood, and not subjected to further treatment in the still. The higher the temperature employed above the end-boiling-point of naphtha, the larger will be the percentage 40 yield of illuminating oil and the smaller will be the percentage yield of naphtha. If a temperature much higher than the end-boiling-point of illuminating oil be employed 45 in the still, the agent will be driven off, resulting not only in the loss of that agent, but also in clogging the pipes.

The still is preferably provided with 50 stirring apparatus of any known and approved form—such as the blades E, E' and the chains F, shown in the drawings—to keep the aluminum chlorid in suspension and in intimate contact with the oil and to prevent overheating it. Preferably also fresh 55 charges of oil are added from time to time through the inlet K to avoid distilling the contents to dryness and to obtain the advantage of the repeated use of the agent, the 60 efficiency of which appears to persist for a considerable time. If the charge were distilled to dryness, the agent would be lost, coke would be formed and cleaning the still after each charge would be required.

65 If desirable, additional aluminum chlorid

may be added from time to time as required. The use of a larger percentage of anhydrous aluminum chlorid than that named in the above example—say 10 parts to 100 parts of oil, for example—causes the desired reactions to take place much more rapidly.

70 Other equivalent agents may be used in combination with, or in place of, anhydrous aluminum chlorid—such, for example, as anhydrous ferric chlorid and perhaps other substances which, up to this time, I have not had time to try. The use of equivalent agents is included within the scope of my claims. I have found anhydrous ferric chlorid to be a less active agent than anhydrous aluminum chlorid, and that it is necessary to use larger quantities of it to effect the same result.

75 The process above described may also be practised with illuminating oil or lubricating oil as starting materials. It may also be practised with crude oils as the starting material, but it is less advantageous to use crude oil because of its contained impurities.

80 90 What I claim and desire to secure by Letters Patent of the United States, is:—

1. The process of converting hydrocarbons having higher-boiling-points into hydrocarbons having lower-boiling-points, 95 which consists in heating such hydrocarbons in the presence of anhydrous aluminum chlorid to a temperature producing vapor having a temperature above the end-boiling-point of naphtha, but below the end-boiling-point of illuminating oil, maintaining such vapor temperature to separate the oil as naphtha and illuminating oil, condensing the illuminating oil driven off in a preliminary cooling chamber, and conducting the 100 naphtha driven off to a condenser.

105 110 115 120 125 2. The process of converting hydrocarbons having higher-boiling-points into naphtha, which consists in heating said hydrocarbons in the presence of anhydrous aluminum chlorid to a temperature producing vapor having a temperature above the end-boiling-point of naphtha, but below the end-boiling-point of illuminating oil, condensing the illuminating oil driven off in a preliminary cooling chamber, returning said oil to the still to be further acted on whereby higher-boiling oil is converted into naphtha, and conducting the naphtha driven off to a condenser.

130 135 140 145 150 3. The process of converting hydrocarbons having higher-boiling-points into hydrocarbons having lower-boiling-points, which consists in heating such hydrocarbons in the presence of anhydrous aluminum chlorid to a temperature producing vapor having a temperature above the end-boiling-point of naphtha, but below the end-boiling-point of illuminating oil, maintaining such vapor temperature until the greater part 155 160 165 170 175 180

of the oil has been separated as naphtha and illuminating oil, condensing the illuminating oil driven off in a preliminary cooling chamber, and conducting the naphtha driven off to a condenser.

4. The process of converting hydrocarbons having higher-boiling-points into naphtha, which consists in heating said hydrocarbons in the presence of anhydrous aluminum chlorid to a temperature producing vapor having a temperature above the end-boiling-point of naphtha, but below the end-boiling-point of illuminating oil, condensing the illuminating oil driven off in a

preliminary cooling chamber, returning 15 said oil to the still to be further acted on, whereby the greater portion of the higher-boiling oil is converted into naphtha, and conducting the naphtha driven off to a condenser.

In testimony whereof I have hereunto signed my name in the presence of two subscribing witnesses.

GEORGE WILLIAM GRAY.
